[57] ABSTRACT

A compartmented box is folded from a one-piece blank to provide a pair of similar box sections, each box section comprising a rectangular base and four upstanding walls integral with the base, the four upstanding walls of each box section including a first end wall defining an end wall of the box, a second end wall hingedly connected along its upper edge to the corresponding wall of the other box section, and a pair of side walls extending between the end walls, said hingedly connected walls being secured in face to face relation and constituting a double-thickness partition defining a pair of adjacent box compartments.

COMPARTMENTED BOX

This invention relates to boxes, and particularly to a compartmented box capable of being folded from a one-piece blank.

The principal object of the present invention is to provide a box of simple construction suitable for the packing of perishable fruits and like commodities which are especially vulnerable to damage during shipment or storage. Another object of the invention is to provide a one-piece blank a one-piece blank from which such a box can be constructed using standard equipment.

According to the invention there is provided a compartmented box folded from a one-piece blank and comprising a pair of similar box sections, each box section comprising a rectangular base and four upstanding walls integral with the base, the four upstanding walls of each box section including a first end wall defining an end wall of the box, a second end wall hingedly connected along its upper edge to the corresponding wall of the other box section, and a pair of side walls extending between the end walls, said hingedly connected walls being secured in face to face relation and constituting a double-thickness partition defining a pair of adjacent box compartments.

In order that the invention may be readily understood one embodiment thereof will now be described by way of example with reference to the accompanying drawings, in which:

FIG. 1 shows a one-piece blank in accordance with the invention for forming a box suitable for packing bananas;

FIG. 2 shows the configuration of a box at one stage of its formation from the blank shown in FIG. 1, and

FIG. 3 is a partly broken away perspective view of the completed box with tray lid.

The completed box shown in FIG. 3 is constructed from corrugated cardboard or like material and comprises a pair of similar box sections 10, 11 separated by a partition 12 of double-thickness. Each box section comprises a rectangular, in this case square, base 13 (or 13') with four upstanding walls 14, 15, 16, 17 (or 14', 15', 16', 17') integral with the base. The walls 14, 14' from the end walls of the box and are formed with cut out openings 18, 18' which enable the box to be lifted easily and also serve as ventilation openings for the contents of the box. Additional ventilation openings may be provided if necessary. The side walls 15, 15' and 16, 16' of the box sections provide the sides of the box. The walls 17, 17' are hingedly connected along their common edge 19 and are secured in face to face relation by complementary locking tabs 20, 20' and slots 21, 21' formed in these walls. The bottom of the box is provided with a peripheral rim 22 surrounding the base of each box section.

It will be seen that the box section bases 13, 13' defining the bottom of the box lie in a common horizontal plane which is spaced from the floor by the depth of the rim 22. The upper edge of the box lies in a second horizontal plane, and each of the side walls 15, 15', 16, 16' is formed with a stepped upper edge providing a pair of edge portions and an intermediate portion 23. The four intermediate portions 23 lie in a common horizontal plane between said first and second planes, and define a level to which the box may be filled. The lid 24 is a conventional inverted tray shaped lid having a depend-

ing peripheral flange 25 which fits onto the top of the box.

Further features of the box construction will be better appreciated from the following description of the method by which it is formed.

The box blank shown in FIG. 1 is of rectangular shape and is formed with a pair of longitudinal fold lines 26, 27 defining a medial strip and a pair of edge strips of equal width. The medial strip is divided by 10 three equally spaced transverse fold lines 28, 29, 30 into four panels of equal width, namely a pair of end panels 31, 32 and a pair of intermediate panels 33, 34. A first longitudinal cut 35 bisects the end panel 31, and a second longitudinal cut 36 bisects the end panel 32 15 and the adjacent intermediate panel 34. The other intermediate panel 33 is bisected by a longitudinal fold line 37 which is aligned with the longitudinal cuts 35 and 36. The medial strip is extended at one end to provide a glue flap 38, which is in fact bisected by the cut 20 36. The edge strips are each divided into four rectangular flap members by transverse cuts 38, 40, 41, and 39', 40', 41', the flap members being hingedly connected to the panels 31, 32, 33, 34 at the fold lines 26, 27.

A second pair of longitudinal fold lines 42, 43 extending along the edge strips providing in each of the flap members a narrow region, such as the region 44, adjacent to the medial strip, and a region, such as the region 45, of greater area. Each of the narrow regions 44 is adapted to provide in the completed box a flange 30 contiguous with the lower edge of a respective upstanding wall and extending upwardly therefrom, the flanges forming the peripheral rim 22 to the base of each box section. The regions 45 are adapted to provide the main support area forming the box bottom as hereinafter described.

The end panel 32 is formed with a pair of openings as shown to provide the ventilation openings 18, 18' in the completed box. The intermediate panel 33 is formed with a pair of slots 21, 21' and a pair of stamped out tabs 20, 20' to provide the locking tabs and slots shown in FIG. 3. Each of the panels 31 and 34 has a cut away area 31', 34' to provide the stepped upper edges of the side walls of the box.

To form the box the rectangular blank is first folded at right angles about the transverse fold lines 28, 29, 30 and the glue flap 38 is glued or otherwise secured to the opposite end of the medial strip, i.e., to the edge of the panel 31. The resultant configuration is a partially split tube as shown in FIG. 2.

The ends of the tube are formed by the sets of flap members, which are first folded inwards about the fold lines 26, 27, and then at right angles about the fold lines 42, 43. Each end of the tube is then closed by superposing one pair of flap members on the other pair and securing the superposed flap members by staples. The closed ends of the tube are thus adapted to constitute the bottoms of the box sections.

The tube is next folded about the fold line 37 to bring the two ends of the tube into alignment, the two halves of the panel 33 thus being brought into face to face relation and secured together by the locking tabs and slots 20, 20', 21, 21', to form the partition 12.

The box is particularly well suited for the packing of bananas and other perishable fruits. The construction of the box, which is suitably of corrugated cardboard, is such that a plurality of such boxes can be stacked in a column without damaging the contents since the par-

titions 12 of the boxes support the greatest part of the load. In this connection it is important to note that the partition 12 is of double thickness, and being integral with the remainder of the box cannot be removed, displaced or readily crushed.

Other important advantages of the box construction may be noted as follows:

i. the stepped upper edges of the box sides define a level to which the box may be filled without the risk that pressure exerted on the lid will be transmitted to the contents of the box;

ii. the locking tabs and slots by which the box sections are secured avoid the need for staples or other metal fastenings which might be injurious to the fruit;

iii. the peripheral rim 22 at the bottom of the box enables the bases of the box sections to be inset so that they are cushioned.

iv. the construction is such that the box can be produced on standard cutting, slotting and creasing equipment and handled as any ordinary RSC box; erection and securing are simple and fast, and a box of considerable strength is very economical to produce.

To facilitate stacking and palletizing the box preferably consists of two identical square box sections. If necessary, liners of paper, polyethylene or other suitable materials may be added.

What I claim as my invention is:

1. A compartmented box folded from a one-piece blank and comprising:

a pair of similar box sections, each box section comprising a rectangular base and four upstanding walls integral with the base,

the base of each box section being formed by four folding flaps constituting integral extensions of the respective upstanding walls, one pair of flaps being superposed on the other pair of flaps and secured thereto,

the four upstanding walls of each box section including a first end wall defining an end wall of the box, a second end wall hingedly connected along its upper edge to the corresponding wall of the other box section, and a pair of side walls extending between the end walls, said hingedly connected walls being secured in face to face relation and constituting a double-thickness partition defining a pair of adjacent box compartments, and

said rectangular bases lying in a first horizontal plane and defining the box bottom, the upper edges of the end walls lying in a second horizontal plane spaced a predetermined distance from the first plane, each of said side walls having a stepped upper edge providing a pair of edge portions contiguous with the upper edges of the end walls and lying in the second plane, and an intermediate edge portion, the intermediate edge portions lying in a third horizontal plane between the first and second planes.

2. A compartmented box according to claim 1, wherein the bases of the box sections are square.

3. A compartmented box folded from a one-piece blank and comprising:

a pair of similar box sections, each box section comprising a rectangular base and four upstanding walls integral with the base,

the base of each box section being formed by four folding flaps constituting integral extensions of the respective upstanding walls, one pair of flaps being superposed on the other pair of flaps and secured thereto,

the four upstanding walls of each box section including a first end wall defining an end wall of the box, a second end wall hingedly connected along its upper edge to the corresponding wall of the other box section, and a pair of side walls extending between the end walls, said hingedly connected walls being secured in face to face relation and constituting a double-thickness partition defining a pair of adjacent box compartments,

each flap being formed with a crease defining a main support area and a narrow flange contiguous with the lower edge of the respective wall and extending upwardly therefrom to provide a peripheral rim to the base of each box section, and

said rectangular bases lying in a first horizontal plane and defining the box bottom, the upper edges of the end walls lying in a second horizontal plane spaced a predetermined distance from the first plane, each of said side walls having a stepped upper edge providing a pair of edge portions contiguous with the upper edges of the end walls and lying in the second plane, and an intermediate edge portion, the intermediate edge portions lying in a third horizontal plane between the first and second planes.

4. A compartmented box folded from a one-piece blank and comprising:

a pair of similar box sections, each box section comprising a rectangular base and four upstanding walls integral with the base,

the base of each box section being formed by four folding flaps constituting integral extensions of the respective upstanding walls, one pair of flaps being superposed on the other pair of flaps and secured thereto,

the four upstanding walls of each box section including a first end wall defining an end wall of the box, a second end wall hingedly connected along its upper edge to the corresponding wall of the other box section, and a pair of side walls extending between the end walls, said hingedly connected walls being secured in face to face relation and constituting a double-thickness partition defining a pair of adjacent box compartments,

each flap being formed with a crease defining a main support area and a narrow flange contiguous with the lower edge of the respective wall and extending upwardly therefrom to provide a peripheral rim to the base of each box section,

each of said hingedly connected end walls being formed with a locking tab positioned to engage a slot in the other end wall for securing said end walls in face to face relation, and

said rectangular bases lying in a first horizontal plane and defining the box bottom, the upper edges of the end walls lying in a second horizontal plane spaced a predetermined distance from the first plane, each of said side walls having a stepped upper edge providing a pair of edge portions contiguous with the upper edges of the end walls and lying in the second plane, and an intermediate edge portion, the intermediate edge portions lying in a third horizontal plane between the first and second planes.

5. A compartmented box according to claim 4, wherein at least said first end walls or said side walls are formed with ventilating openings.
